(57) **CLAIM**

I claim, the ornamental design for a blind for windows, as shown and described.

DESCRIPTION

FIG. 1 is a perspective view, of the blind for window showing my new design in a position of use;

FIG. 2 is a perspective view thereof;

FIG. 3 is a front elevational view thereof;

FIG. 4 is a rear elevational view thereof;

FIG. 5 is a right side view thereof;

FIG. 6 is a left view thereof;

FIG. 7 is a top view thereof; and,

FIG. 8 is a bottom view thereof.

The broken lines depict environment that forms no part of the claimed design.

1 Claim, 6 Drawing Sheets
